US00D957520S

(12) **United States Design Patent** (10) **Patent No.:** **US D957,520 S**
Fish et al. (45) **Date of Patent:** **** Jul. 12, 2022**

(54) **NOTEBOOK**

- (71) Applicant: **WORKLIFE BRANDS LLC**,
Framingham, MA (US)
- (72) Inventors: **Robert Fish**, Worcester, MA (US);
James Bishai, Dorchester, MA (US);
Jessica Hedge, Waltham, MA (US);
Seda Evis McPhee, Brooklyn, NY
(US); **Ayse Birsel**, New York, NY (US);
Leah Caplan, Glen Ridge, NJ (US)
- (73) Assignee: **WORKLIFE BRANDS LLC**,
Framingham, MA (US)
- (**) Term: **15 Years**
- (21) Appl. No.: **29/716,539**
- (22) Filed: **Dec. 10, 2019**
- (51) LOC (13) Cl. **19-04**
- (52) U.S. Cl.

Primary Examiner — Lauren D McVey(74) *Attorney, Agent, or Firm* — Sheridan Ross P.C.(57) **CLAIM**

The ornamental design for the notebook, as shown and described.

DESCRIPTION

FIG. 1 is a perspective view of a notebook, showing our new design;

FIG. 2 is a front elevation view thereof;

FIG. 3 is a rear elevation view thereof;

FIG. 4 is a right elevation view thereof;

FIG. 5 is a left elevation view thereof;

FIG. 6 is a top plan view thereof; and,

FIG. 7 is a bottom plan view thereof.

The broken lines immediately adjacent to the shaded areas depict the bounds of the claimed design, while all other broken lines are directed to environment. The broken lines form no part of the claimed design.

1 Claim, 5 Drawing Sheets(58) **Field of Classification Search**
